UNITED STATES PATENT OFFICE.

WILLIAM A. NICHOLS, OF FALL RIVER, MASSACHUSETTS, AND THOMAS P. HIMES, OF PROVIDENCE, RHODE ISLAND.

WIRE-BOARD CLEANER FOR DRAWING AND SPINNING MACHINES.

No. 922,806.

Specification of Letters Patent.

Patented May 25, 1909.

Application filed June 9, 1908. Serial No. 437,534.

To all whom it may concern:

Be it known that we, WILLIAM A. NICHOLS, residing at Fall River, in the county of Bristol and State of Massachusetts, and THOMAS P. HIMES, residing at Providence, in the county of Providence and State of Rhode Island, both citizens of the United States, have invented certain new and useful Improvements in Wire-Board Cleaners for Drawing and Spinning Machines, of which the following is a specification, reference being had therein to the accompanying drawing.

This invention relates to wire board cleaners for drawing and spinning frames and the like, and has for its object to provide a simple, practical and effective hand operated portable brush or cleaner adapted to be passed along the wire board beneath the yarn leading from the rolls to the guide eyes, to collect the flyings and foreign matter there deposited.

Our improved cleaner is preferably constructed of a combination of flexible bristles and coarse woolen cloth, felt, or other suitable flexible material, secured to a suitable body portion, block, or backing, and the whole is incased, covered or inclosed in such a way that the extending bristles are effectually prevented from reaching out, engaging and breaking down the yarn ends under which the same is passing.

Another feature of the invention is that said casing is also arranged to extend over the edge of the wire board and serve as a guide by which the cleaner may be easily controlled and kept in the right path or position while being passed quickly beneath the running threads.

Still another feature is that by the use of this casing the lint and other foreign matter thus collected is rolled up and retained beneath the same and effectually prevented from getting out and becoming engaged and carried away by the rapidly running yarn.

With these objects in view, the invention consists of certain novel features of construction, as will be more fully described and particularly pointed out in the appended claims.

In the accompanying drawings: Figure 1—is an end view showing the rolls and the wire board on a drawing or spinning frame and our improved cleaner in position thereon. Fig. 2—is a detail showing an enlarged end view of the cleaner in section. Fig. 3—

is a sectional side elevation on line 3—3 of Fig. 2 looking in the direction of the arrows. Fig. 4—is a plan view looking at the underneath side of the cleaner.

Referring to the drawings, at 1 is the wire board of the ordinary drawing and spinning frame, along the outer edge of which is placed the guide eyes 2 through which the yarns 3 from the drawing rolls 4 are passed. Our improved cleaner is designed to set on 60 this wire board, and is constructed of a body portion or block 5, which may be made of wood, or any desired material. The lower face of this block is grooved, as at 6, throughout its length so as to fit over the hinge portion 7 of the wire board. The rear portion of the block at 8 is also cut away to fit over the hinge 9 of this board. The face of the block is provided preferably with a piece of felt, or coarse woolen cloth 10, the same being adapted to extend beyond the back edge of said block forming a flap 11, which is adapted to reach over and wipe the roller beam 12 and also to readily rise into the position illustrated in Fig. 1 when passing the 70 standards 13. A row of bristles 14 are adapted to extend forward from the front edge of this block for collecting the waste, which bristles may be secured in any convenient manner to the block. 75

The essential feature of our improved cleaner is that a shield or casing 15 is provided, secured to the block in any convenient manner, and is adapted to extend over and around the bristles 14 to form a shield to 80 protect the yarn and prevent said bristles from reaching out to engage and break down the ends. This shield is also adapted to extend over along the side of the device, as at 85 16, its lower edge 17 extending down below the bottom of the block over the edge 18 of the wire board to form a guide to control the path of movement of said cleaner so that the same may be passed rapidly under the yarns without the danger of moving out of its regular path and breaking down any of the ends. 95

The ordinary brush or wire board cleaner in being passed beneath the rapidly running yarns has no means of guiding it straight, the bristles reach out and break the ends, the 100 collected waste and flyings roll up, work off to one side, engage the rapidly running yarns and are carried off by them, thus defeating the very object of the cleaner, and said cleaners have therefore been quite unsatisfactory 105

for this purpose. Our improved device has been particularly constructed to obviate all of the above difficulties, the same being adapted to clean and wipe the whole width 5 of the wire board and also reach out and wipe that portion of the frame between the standards. The bristles are all housed in so that they cannot reach out, engage and break down the ends. A simple and effective guide is also provided whereby it is practically impossible for said cleaner while being passed rapidly beneath said arms to get out of its proper path, and the waste and flyings are engaged, rolled up, collected and 10 retained beneath the casing, thus effectually preventing the same from getting out and becoming entangled with the rapidly running 15 yarns.

This device is extremely simple and inexpensive in construction, effective in its operation, and by its use an unskilled workman 20 may quickly clean a wire board without breaking down the ends of the yarn.

Having thus described our invention, what 25 we claim as new and desire to secure by Letters Patent, is:

1. A wire board cleaner, comprising a body portion a brush attached to said body for engaging and collecting the waste, and a casing 30 over said collecting brush to prevent its engagement with the yarn, said casing also forming a receptacle for retaining the collected waste.

2. A wire board cleaner, comprising a body, 35 a brush attached to said body for engaging and collecting the waste, a casing over said collecting brush to prevent its engagement

with the yarn, said casing also forming a receptacle for retaining the collected waste, and means for guiding said body to control 40 its path of movement.

3. A wire board cleaner comprising a portable body, a brush extending outward from the end of said body for engaging and collecting the waste, and a casing over said brush 45 to prevent engagement with the yarn, said casing also forming a receptacle for retaining the collected waste and a guide for controlling the path of movement of said cleaner.

4. In a wire board cleaner, a body portion, 50 a brush attached to the end thereof, a casing over said brush to protect the yarn and retain the collected waste, said casing being also adapted to extend around and engage the edge of the wire board to form a guide for 55 controlling the path of movement of said cleaner.

5. In a wire board cleaner, a body portion, 60 a brush attached to the end thereof, a casing over said brush to protect the yarn and retain the collected waste, flexible waste collecting means also attached to said body and adapted to extend over the roller beam, and a guide for controlling the path of movement of said cleaner.

In testimony whereof we affix our signatures in presence of two witnesses.

WM. A. NICHOLS.
THOMAS P. HIMES.
